UNITED STATES PATENT OFFICE

169,830

COMBINED SALAD FORK AND KNIFE

Judy A. St. Clair, Fort Worth, Tex.

Application June 19, 1952, Serial No. 20,280

Term of patent 14 years

(Cl. D44—29)

To all whom it may concern:

Be it known that I, Judy A. St. Clair, a citizen of the United States, residing at Fort Worth, in the county of Tarrant and State of Texas, have invented a new, original, and ornamental Design for a Combined Salad Fork and Knife of which the following is a specification, reference being had to the accompanying drawing, forming part thereof, wherein:

I claim:

The ornamental design for a combined salad fork and knife, as shown.

JUDY A. ST. CLAIR.
